COTTON GIN AND CLEANER

Dan C. Griffin, Jackson, Miss., assignor to Centennial Cotton Gin Company, Columbus, Ga., a corporation of Georgia

Application November 17, 1938, Serial No. 241,048

3 Claims. (Cl. 19—59)

This invention relates to cotton gins and cleaners and to a method of removing sand, trash, motes or shales during the process of ginning the cotton in the usual manner.

In the operation of the ordinary cotton gins; and particularly in cotton gins employing an air blast for removing the lint from the gin saws, the motes, fine trash and dirt thrown off by centrifugal force, and dropped by gravity when released through the ginning ribs, will be dropped into the open lint flue opening, or will be pulled into the lint flue by the normal pull over. This reduces the grade of the ginned lint, and is undesirable as it reduces the selling price. It is the desire of spinners and sellers as well to find some way or process whereby as much as possible of the mote, trash and shale with all the dirt possible should be removed in the process of ginning.

Heretofore it has been the practice of textile mills to install cleaning equipment for the removal of the motes, trash, sand and shale from the ginned lint cotton. In this recleaning process considerable weight is lost and the price of the baled cotton is reduced in this same ratio. It is therefore the purpose of this attachment to remove all or as nearly as possible all the foreign matter, thereby raising the grade and selling price of the cotton delivered directly from the cotton gin plants.

It is the main object of the present invention, therefore, to provide a cotton gin of standard construction, so far as the hulling and ginning operations are concerned, with means for removing the fine trash, motes or shale during the actual ginning of the cotton and by a reverse blower or suction action in cleaning the cotton at the thinnest part of the bat as it passes from the roll box toward the lint flue. In other words, the object of this invention is to eliminate the step of re-cleaning lint cotton which has heretofore been necessary to clean lint contaminated by sand, shale, fine trash or motes which have not been removed in the ordinary process of ginning.

Other objects of the invention will become apparent as the detailed description thereof proceeds:

In the drawings:

Figure 1 is a central, vertical section of a cotton gin provided with the cleaning mechanism which forms the essential element of the present invention;

Figure 2 is a horizontal section, to an enlarged scale, taken on the line 2—2 of Figure 1;

Figure 3 is a vertical transverse section, also to an enlarged scale, taken on the line 3—3 of Figure 1; and

Figure 4 is a fragmentary perspective of a detail of construction.

Figure 5 is a view similar to Fig. 1 showing the application of the invention to a gin having rotary brushes.

As shown in the drawings, the machine embodies the usual saw cylinder 5 mounted for rotation on the shaft 6 journaled at its opposite ends in the framework 7 common in cotton gins for rotation by any suitable source of power.

The seed cotton is fed into the huller front 8, where the hulls, etc., are removed in the usual manner by the huller ribs 9. The cotton, with the hulls removed, is drawn upwardly on the teeth of the saws into the roll box 10 where it is ginned by the action of the ginning ribs 11. The lint as it is carried around by the saws through the slots between adjacent ginning ribs is still contaminated with shale, sand, fine trash and motes. Attempts made heretofore to remove this contaminating matter have not been very successful; and the resulting lint discharged by the cotton gin has had to be recleaned in order to enhance its quality and adapt it for sale at a higher price.

The present invention begins at that line L of the gin where the cotton bat passes through the ginning ribs from the roll box. Beyond this line, the cotton bat is at its thinnest. Consequently, the motes and trash can be most readily removed from this portion of the bat; providing the air blast is properly directed against the lint.

In the form of the invention as shown in Figure 1, the invention comprises the usual cylindrical air blast chamber 12 connected at its upper and lower sides tangentially to the partitions 13 and 14 which extend between opposite end walls of the gin framework and are turned inwardly at their inner ends to form streamlined throats 15 and 16 for the air blasts directed against the lint on the teeth of the saw cylinder.

A partition 17 spaced below the partition 14 extends between the end walls of the gin frame to form a lint duct 18 through which the lint blown off the teeth of the saw cylinder is forced. A valve 19 hinged to the lower partition 17 may be adjusted to regulate the cross sectional area of the inlet end of the lint duct 18. A partition 20 extending between the end walls of the cotton gin and above partition 13 to form with said partition a suction chamber 21 connected

55

at its outer end to the suction pipe 22 which may be suitably valved and connected to a blower or fan (not shown) to apply any necessary or desired degree of suction to the chamber 21. A 5 valve 23 is hinged to the partition 20 at the inner end thereof for adjustment to control the quantity of air drawn in through the air inlet slot 24 into the suction chamber 21.

A deflector 25, including a pair of parallel 10 plates 26 and 27, extends between the vertical end walls of that part of the blast chamber extending from the cylindrical casing 12 to the saw cylinder. The plates 26 and 27 are fixed preferably and symmetrically on opposite sides 15 of a horizontal plane passing through the axis of the cylinder shaft 6. A plate 28, likewise extending between the end walls of the blast chamber, is mounted to slide between the plates 26 and 27 and may be adjusted toward and from 20 the periphery of the saw cylinder by means of the rack 29 formed on one end of the plate 28 and in engagement with an adjusting pinion 30 mounted on a shaft 31 journaled in the end wall of the gin and provided with an operating handle or button 32. Preferably, this rack and pinion is duplicated on the other end wall to enable the adjustment of plate 28 to be effected from either end of the machine.

The outer edge of the sliding deflector plate 30 28 is provided with arcuate flanges 33 and 34 forming an apron having its inner surface concentric with the saw cylinder. By the adjustment of the deflection plate 28, the flanges 33 and 34 carried thereon may be adjusted relative 35 to the end of the partitions 13 and 14 to vary the cross sectional areas of the throats 15 and 16 through which the air blast of the blast chamber 12 is directed in opposite directions on the lint adhering to the teeth of the saw cylinder. 40 The blast through throat 15 removes shale and motes while that through throat 16 removes the clean lint from the saw.

In the Figure 5 is illustrated a brush gin in which the brush 35 operates as usual to brush 45 the lint from saw 5 while brush 36 operating in the opposite direction brushes the lint back onto the saw and sets up a current of air impelling the dirt particles out through flue 21. In this form the baffle 33' functions to separate the lint 50 cleaning and removing brushes and blasts.

The saws of a cotton gin cylinder are very thin, being about .032 to .038 of an inch thick; and the teeth are small and sharp so that each tooth carries but few fibers of lint. These fibers 55 remain on the teeth until they are blown off the saws as they pass below the nozzle for the air blast formed by the throat 16. The cotton fibers trail on each side of the saws while suspended on the teeth. Because of the high speed of the 60 saws, the trailing fibers tend to spread out from each other. In this condition, the fibers are carried toward the air jet formed by the blast directed upwardly through the throat 15. Since 65 this blast of air through the throat 15 is directed oppositely to the direction of rotation of the saws, the fibers are held against the saw teeth and folded back. The pressure of this air jet takes off the fine trash, motes and shale carried by the ginned lint on the saw teeth. The foreign matter dropped by gravity or thrown off from 70 this lint by centrifugal force, or taken off by the air blast, is carried through the slot 24 and duct 21 and the chamber 2 to a place outside the gin house.

It is evident that due to the upwardly directed blast through the throat 15 and tangentially against the saw teeth, the lint fibers are held on the teeth, but the motes and fine trash thrown off by centrifugal force are trapped in the suction chamber 21 and removed from the gin. As 5 the cleaned lint passes downwardly beyond the jet from the throat 16, the air blast is now directed in the same direction as the teeth of the saw. Consequently, the lint is blown from this 10 lower part of the saw cylinder into the lint duct 18 suitably connected to a lint flue (not shown).

The cotton fibers, while passing through the end of the suction chamber, are carded and stratified, and thereby prevented from matting 15 and breaking in subsequent operations.

As the lint passes through the suction chamber, the cotton is in its best shape and in its thinnest bat or spread. The motes and other particles separate from the lint as it passes 20 through the ginning ribs at their upper ends. Consequently, the air blast applied in the reverse direction against the cotton fibers on the saw teeth removes all or practically all of the foreign matter from the lint, and in doing so, is applied 25 to the least possible number of pounds of cotton. The suction applied at this point in the travel of the saw cylinder assists in the cleaning action, since it pulls all the fine trash, shale and dirt along with the mote, to a point outside the 30 gin house.

While the drawings show this cleaner attachment as forming a part of the cotton gin itself, it must be understood that this system can be applied to any gin or system of gin of standard 35 construction without change in principle of these standard gins as heretofore manufactured. It must also be understood that the invention is not to be considered as limited to the particular details of construction illustrated and described 40 herein, nor in any other manner except as indicated by the scope of the claims appended hereto.

What I claim is:

1. In a cotton gin having a rotary saw cylinder and ribbed box, means for cleaning the cotton on the saw and doffing the cleaned cotton therefrom comprising substantially parallel spaced walls extending between the end walls of the gin and terminating adjacent the periphery of the saw in inwardly directed flanges, substantially concentric with the saw cylinder, a combined deflector plate and gate of substantially T-shape in cross section, coextensive in length with said flanges and positioned intermediate thereof with means for supplying a blast of air 55 between said spaced walls, whereby said air blast will be divided by said deflector plate and directed between same and said flanges in opposite directions tangential to the saw cylinder.

2. Claim 1 with means for adjusting the deflector plate toward and away from the saw cylinder whereby the opposed tangential air jets may be simultaneously modified.

3. Claim 1 with walls coextensive with the spaced walls specified and positioned above and 65 below the same respectively to constitute flues for the removal separately of dust and dirt in the upper and the cleanest lint in the lower, with means for applying suction to the upper flue as specified.

DANIEL C. GRIFFIN.
